SOFTENING LEATHER BY APPLICATION OF AN ACETYLATED MONOGLYCERIDE
Gerard Warren Curtis, Fair Lawn, N.J., assignor to American Cyanamid Company, Stamford, Conn., a corporation of Maine
No Drawing. Filed Mar. 6, 1964, Ser. No. 350,097
1 Claim. (Cl. 8—94.22)**ABSTRACT OF THE DISCLOSURE**

A process is provided for softening aged leather which involves swabbing said leather with either liquid monoacetyl glycerol dioleate or liquid diacetyl glycerol monooleate.

The present invention relates to an improved process for treating leather. More particularly, it relates to a process for softening aged leather. Still more particularly, the invention is concerned with an improved process for softening aged leather by the application of an acetylated monoglyceride.

It has been an ever growing concern to leather technologists to prevent leather from ultimately hardening and becoming both slippery to the touch and even brittle due to its tendency to dry out on aging. In all applications of leather, continued use renders the leather smooth and slippery to the touch, thereby requiring frequent replacement where a non-slippery, slightly tacky and resilient surface is required. Thus, to remedy this situation, various procedures have been suggested in the past. One such procedure has been to swab aged leather with sulfonated, castor oil and other soaps to restore it. Unfortunately, this procedure is not entirely satisfactory, for the reason that the treatment is not long lasting. Another procedure is in the application of saddle soap. Any benefit derived therefrom is also short-lived, in that the soap remains on the leather surface for only a short period of time. This treatment merely affects the surface. There is no effective penetration. A still further treatment of leather resides in the use of rosin preparations. Most such rosin preparations contain wax to soften the leather. Again, wax compositions do not ordinarily penetrate leather beyond the surface of leather. Further, low melting point waxes are readily removed by the touch of a warm or perspiring hand. In a relatively short period of time, the rosin preparation-treated leather reverts to its non-useable state. If a leather-treating material could be developed such that it penetrates leather and is long lasting, such a composition would be highly desirable.

It is, therefore, a principal object of the present invention to provide a leather-treating material which can be economically and readily applied to leather so as to either maintain its original newness or to restore the same to its original state. It is a further object of the invention to provide a leather-treating material which can penetrate the surface of leather and maintain or restore the leather to its original state for a prolonged period of time. Other objects and advantages will be determined from a consideration of the ensuing disclosure.

To this end it has been unexpectedly found that either new leather can be maintained or aged leather can be restored to its original state economically and rapidly by providing for the topical application thereof with an acetylated monoglyceride. The latter being applied as a liquid penetrates the surface of leather upon application.

The invention will be particularly described with respect to aged leather grips on golf clubs. Although the

2

leather thereon is frequently exposed to elevated temperatures and to resultant hand perspiration, it is exposed also to low temperatures, even freezing temperatures. Such exposure clearly falls within the contemplation of the avid golfer. In a low temperature environment, gripping of the club is exceedingly difficult in that it becomes exceedingly slippery but for the treatment contemplated by the present invention.

When leather on golf clubs is new, it is soft and tacky, thereby providing for easy gripping of the club. However in time, usually within a year or more, the leather on a golf club becomes unduly slippery, smooth and hard. To restore the leather to its original state, it has been found unexpectedly that an acetylated monoglyceride, comprising either diacetylated glycerol monooleate or monoacetylated glycerol dioleate, can be applied to leather by merely swabbing the oleate material thereon, and wiping or otherwise removing excess compound. Within not more than about 24 hours, the leather has been restored to its original state. Further, with ordinary use, the leather need not be retreated within an extended period of six months or more. Where the leather is constantly exposed and used, the required period for retreatment is somewhat shortened or reduced, usually to within a month or two.

As stated above, the acetylated glycerol oleate leather-treating material employed herein may be either monoacetyl glycerol dioleate or diacetyl glycerol monooleate. In either form, the oleate is a liquid and usually possesses an acid number of one or less, a saponification number of 375—385, an iodine value of 50—60, an hydroxyl value of over 30, and percent monoglyceride equal to 1% or less. The diacetyl glycerol monooleate is prepared by reacting two mols of acetic anhydride with one mol of glycerol monooleate. Similarly, the monoacetyl glycerol dioleate is prepared by reacting one mol of acetic anhydride with one mol of glycerol dioleate.

Advantageously other liquid acetylated glycerol high fatty acid esters can be employed. Such high fatty acid esters are, for instance, those containing from 12 to 22 carbon atoms, and more specifically include laurylates, palmitates, linoleates and equivalents thereof.

Although the invention has been described with respect to the treatment of leather on a golf club, it advantageously can be applied to the treatment of leather in general, as for instance, the treatment of the uppers of leather shoes, leather gloves and the like.

I claim:

1. A process for softening aged leather which consists essentially in: swabbing the said aged leather with a treating agent selected from the group consisting of liquid monoacetyl glycerol dioleate and liquid diacetyl glycerol monooleate, said treating agent possessing a saponification number of from 375 to 385, an iodine value of from 50 to 60 and a percent monoglyceride equal to not more than 1%, and, thereafter, removing any excess treating agent.
